(57) **CLAIM**

The ornamental design for a 3D printer table, as shown and described.

DESCRIPTION

FIG. 1 is a front, left and top perspective view of a 3D printer table, showing my design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of portion 9 shown in FIG. 1; and, FIG. 10 is an enlarged view of portion 10 shown in FIG. 2; The small evenly spaced dashed broken lines in the drawings illustrate the portions of the 3D printer table that form no part of the claimed design. The dot-dash broken lines encircling portions of the 3D printer table in FIGS. 1 and 2, and illustrated in enlarged views in FIGS. 9 and 10 also form no part of the claimed design.

1 Claim, 10 Drawing Sheets
